(**) Term: **14 Years**

(57) **CLAIM**

(21) Appl. No.: **29/254,046**

The ornamental design for an inhalation device, as shown and
described.

(22) Filed: **Feb. 16, 2006**

DESCRIPTION

(51) **LOC (9) Cl.** 29-02

FIG. 1 is a front perspective view of an inhalation device
according to a first embodiment.

(52) **U.S. Cl.** D24/110

FIG. 2 is a rear perspective view of the inhalation device of the
first embodiment.

(58) **Field of Classification Search** D24/110,
D24/110.1; 128/203.15, 200.23, 200.14,
128/203.13, 200.21

FIG. 3 is a front view of the inhalation device of the first
embodiment.

See application file for complete search history.

FIG. 4 corresponds to FIG. 1 but with the inhalation device in
an alternative configuration.

(56) **References Cited**

FIG. 5 is a further rear perspective view of the inhalation
device of the first embodiment in the alternative configura-
tion.

U.S. PATENT DOCUMENTS

FIG. 6 is a front perspective view of an inhalation device
according to a second embodiment.

FIG. 7 is a rear perspective view of the inhalation device of the
second embodiment.

FOREIGN PATENT DOCUMENTS

FIG. 8 is a front view of the inhalation device of the second
embodiment.

WO WO 0224263 A2 3/2002

FIG. 9 corresponds to FIG. 6 but with the inhalation device in
an alternative configuration; and,

FIG. 10 is a further rear perspective view of the inhalation
device of the second embodiment in the alternative configura-
tion.
